ANTENNA ARRAY

Armig G. Kandoian, New York, N. Y., assignor to
 Federal Telephone and Radio Corporation,
 Newark, N. J., a corporation of Delaware

Application December 16, 1942, Serial No. 469,173

6 Claims. (Cl. 250—11)

1

This invention relates to antenna arrays and more particularly to antenna arrays constructed to provide different energization of different antenna units in the array.

It is often desired to provide an array of antenna units in which energy is distributed to provide different current levels in different antenna units. An example of such an array is the so-called binomial array wherein the antenna elements are spaced at regular intervals and are energized with currents decreasing from the center outwardly in accordance with the exponents of a binomial expansion series. In the past, quite complex feeding arrangements have generally been used in order that the transmission line may be properly adjusted to feed different currents to the different antenna units.

It is an object of my invention to provide an antenna array in which the antenna units are energized at different current levels without the necessity of providing variable or adjusted impedance characteristics in the feeder line connected to the antenna.

It is a further object of my invention to provide an antenna array in which the antenna elements themselves have selectively different impedances to control the current level of energy supplied thereto.

This invention is based upon the following two impedance characteristics of radiators. First, when a radiator substantially one electrical wavelength is fed at its center, the input impedance is a function of the ratio of diameter to the length of the radiator. As the diameter is increased the impedance is reduced. Hence, by varying the diameter of the radiator its impedance may be controlled.

Secondly, when a half wavelength radiator is fed at its center, the impedance is substantially independent of diameter of the radiator. However, if its length is made more than a half wavelength, quarter wave each side of center, the impedance will become substantially higher.

According to a feature of my invention, a plurality of linear antenna elements forming an array are coupled individually to a transmission line, said antenna elements being given different impedance characteristics in accordance with a desired current level in each of the respective antenna units. This may be accomplished by making the conductors of the antenna unit of different selected diameters or by making them of different selective lengths so that they will present the desired impedance. In the latter case it may be necessary to supply phasing ele-

2

ments for the shorter antenna units to maintain the desired phase relationship of energization therein.

A better understanding of my invention and the objects and features thereof may be had by reference to the accompanying drawings in which:

Fig. 1 illustrates an antenna array in accordance with the features of my invention;

Fig. 2 is a modified array in accordance with my invention;

Fig. 3 is a still further modification of an antenna array constructed in accordance with my invention; and

Fig. 4 is still another modification of an array incorporating the features of my invention.

Turning first to Fig. 1, 10 is a translating device connected by means of transmission line 11 and branch lines 12 and 13 to an antenna array 14 made up of elements 14, 15, 16, 15A and 16A. Each element is made up of two radiators substantially one half wavelength each. Successive elements are spaced one half wavelength apart. The translating unit 10 may be either a transmitter or a receiver. In branch lines 12 and 13 are provided transpositions 17, 18 and 19, 20, respectively.

Considering the translating unit 10 as a transmitter, energy therefrom is fed over line 11 directly to central element 14 and over branch lines 12 and 13 to the successive units 15, 16 and 15A, 16A, respectively. Elements 15, 15A and 16, 16A are made successively smaller in diameter than central element 14 so that they present successively higher impedance across the feeder line. Accordingly, the current in the antenna units will be successively lower as the outer ends of the array are approached.

If the antenna units are spaced apart one half of a wavelength at the operating frequency and are properly designed in diameter to have the currents therein distributed from the center outwardly in accordance with the exponents of a binomial expansion, then a normal binomial array is provided. By the use of the feeder system illustrated, the feeder line may be made to have substantially uniform impedance throughout and thus the feeding of the antenna elements is greatly simplified. It is only necessary to select suitable diameters for the individual antenna units in order that the desired distribution of energy may be achieved.

In Fig. 2 is illustrated a six element antenna array fed by transmission line 11 and branch lines 12 and 13 similar to those shown in Fig. 1.

However, in this figure, no transpositions are provided between the successive antenna elements 21, 22, 23 and 21A, 22A and 23A. Accordingly, the antenna units are energized alternately in phase opposition if the spacing is maintained at a half wavelength. A transposition is provided at 24 in order that the two sides of the array may maintain the pattern of phase opposition. It is clear that the system may, if desired, be fed in the same manner as the antenna elements of Fig. 1 if cophasal energization of the antenna units is desired.

In Fig. 3 is shown a further modification of my invention in which is provided feeder line 11 and branch lines 12 and 13 provided with transpositions 30 and 31. To branched lines 30 and 31 are coupled antenna units 32, 33 and 32A, 33A, respectively. In order to give different impedance characteristics to the separate antenna units, elements 33 and 33A are made greater in length than elements 32, 32A which are made up of two quarter wavelength radiators each. Accordingly, these elements will present a higher impedance to the transmission line than 32 and 32A which are made equal to a half wavelength at the operating frequency or an equivalent electrical length.

Since elements 33, 33A are not tuned to a half wavelength, they will tend to produce a phase shift in the energy supplied thereto. In order to take care of any such phase shift, individual phase correcting networks 34, 34A are provided. It is clear that with this type of antenna array the desired distribution of energy to the various units may be achieved without altering the impedance characteristics of the transmission line itself. Furthermore, this type of array may be extended in length in the same manner as the arrays shown in Figs. 1 and 2, it being desirable in this case to provide the necessary phase shifting units for each of the antenna elements which departs from a half wavelength-equivalent length.

In Fig. 4 is shown still another modification in which an array of horizontal antenna elements 41, 42, 41A, 42A are arranged to be fed from one end of a line 40. The central antenna elements 41, 41A are made to have a lower impedance than the outer elements 42, 42A to provide the desired current distribution. Also, if the spacing between coupling points to line 40 for the individual units is made equal to half a wavelength at the operating frequency and cophasal energization is desired, transpositions or other phase reversing means may be provided in the alternate individual feed lines 43, 44, 43A, 44A, serving to supply energy to the individual antenna units. If 180° phase of energization of the antenna units is desired so that the array will act as an end-fire array instead of a broad-side array, then the antenna units may be coupled to line 40 without the phase reversing means.

It is clear that the end fed array of Fig. 4 may be applied similarly to other arrays of the type shown in Figs. 1 to 3, inclusive, if desired. Also as many units as desired may be used in the array to provide the desired concentration of the radiation pattern.

Furthermore, the impedance adjustment of the individual units may be achieved in other ways

than by changing of length or diameter as shown herein.

While I have described above the principles of my invention in connection with specific apparatus, and particular modifications thereof, it is to be clearly understood that this description is made only by way of example and not as a limitation on the scope of my invention as set forth in the objects of my invention and the accompanying claims.

What is claimed is:

1. An antenna array in which the antenna elements forming said array are energized at different current levels comprising a feeder line, a plurality of antenna elements coupled to said feeder line at substantially half wave intervals, said antenna elements being made different in impedance in accordance with the desired current level in the respective elements.

2. An antenna array according to claim 1, wherein said antenna elements are made of conductors of different selected diameters to provide the desired impedance characteristics.

3. An antenna array according to claim 1 wherein said antenna elements are constructed with selectively different lengths to provide the desired impedance characteristics, further comprising phase adjusting means for adjusting the phase of current in the shorter of said elements to compensate for the phase shift caused by the difference in length of said elements.

4. An antenna array comprising a feeder line of substantially constant characteristic impedance, a plurality of antenna units coupled to said line at substantially half-wave intervals at the operating frequency and means for reversing the phase of energy in said feeder line between successively arranged antenna units, said antenna units being constructed to have selected different impedance characteristics to provide a predetermined distribution of current therein.

5. An antenna array according to claim 4 wherein said antenna units are made of conductors of different diameter to provide the desired impedance characteristics.

6. An antenna array comprising a feeder line having substantially constant characteristic impedance, a plurality of branch lines of substantially equal length coupled to said feeder line at substantially half wave intervals at the operating frequency, a plurality of antenna units individually coupled to said branch lines and means for reversing the phase of energy of alternate ones of said branch lines, said antenna units being arranged in coaxial juxtaposition and constructed to have selected different impedance characteristic to provide a predetermined distribution of current therein and arranged to be fed from one end thereof.
